UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

SEWING MACHINE.

Application filed August 8, 1922. Serial No. 580,571.

To all whom it may concern:

Be it known that I, JOHN KIEWICZ, a citizen of the United States, and resident of Boston, county of Suffolk, State of Massachusetts, have invented an Improvement in Sewing Machines, of which the following description, in connection with the accompanying drawing, is a specification, like characters on the drawing representing like parts.

This invention relates to button-hole sewing machines and particularly to the work-clamps thereof, and the object of the invention is to provide a novel means for controlling the spreading action of the work-clamps after the button-hole slit has been cut.

Some button-hole sewing machines are arranged so that when they are started in operation the button-hole cutter is first operated to cut the button-hole slit, after which there is a relative movement between the work-holding means and the stitch-forming mechanism to bring the parts from button-hole cutting position into stitching position, and the stitch-forming mechanism is then set in operation to stitch around the edges of the button-hole. It is customary to construct the work-clamping means so that during the movement from button-hole cutting to stitching position the work is stretched slightly transversely of the slit, thereby to spread or open the latter.

My present invention relates to a device for this purpose and has particular reference to means for controlling the amount which the button-hole slit will be spread at any operation.

In order to give an understanding of my invention, I have illustrated in the drawings a selected embodiment thereof, which will now be described, after which the novel features will be pointed out in the appended claims.

In the drawings, Fig. 1, shows a sufficient portion of a button-hole sewing machine to illustrate the construction and operation of my invention, said figure being a plan view of the work-holding means.

Fig. 2 is an underside view of the front portion of the bed frame illustrating part of the control mechanism.

In the drawings, 1 indicates the front portion of the bed frame of a button-hole sewing machine. This is formed at 2 to receive

the two clamp-plates 3 and 4. Each clamp plate is provided with a roughened portion 5, said portions being situated either side of the sewing opening and co-operating with the work-clamp 6, for clamping the work in position. These work-clamps 6, are carried by arms 7 that are pivoted to the clamp plates 3 and 4.

In Fig. 1, 8 indicates the throat plate of the under-thread mechanism, and 9 indicates part of the button-hole cutter.

The parts thus far described are or may be all as usual in button-hole sewing machines and form no part in the present invention. In the operation of these sewing machines, the work is introduced between the work-clamps 6, and the roughened surface 5 of the clamp plates, and the work-clamps are then depressed to clamp the work in position.

After the machine is started, the button-hole cutter operates to cut the button-hole slit and subsequently the clamp plates and stitch-forming mechanism including the throat plate, are moved relatively to each other to bring the button-hole slit over the throat plate 8 and into stitching position, after which the stitch-forming mechanism is set in operation to stitch around the edge of the button-hole.

During such relative movement between the work clamps and stitch-forming mechanism to bring the parts to stitching position, the clamp plates 3 and 4 are spread slightly so as to open the button-hole slit and this spreading operation is accomplished by means of a spreading member 10 having two rounded or cam surfaces 11, which co-operate with rolls 12 carried by the under side of the clamp plates. The spreading member 10 is mounted as usual in sewing machines of this type so that during the relative movement between the throat plate and the work-holding means, there will be a relative movement between the cam surfaces 10 and 12 so that as the cam surfaces wipe past the rolls 12 the clamp plates are spread or separated from each other. The amount of separating movement which is given to the clamp plates in passing the cam surfaces 11, depends upon the initial position of said clamp plates relative to each other.

If the clamp plates are initially at the limit of their movement toward each other, then they have a greater spreading action.

as the rolls 12 pass the rounded surface 11, than if the clamp plates were initially separated slightly.

I have provided herein means for normally controlling the initial position of the clamp plates and thereby determining the degree of spreading movement.

In the construction herein shown, each clamp plate has a plate 13, connected thereto, which is provided with a slot 14, in which operates a pin 15, secured to the end of a lever 16, situated on the underside of the bed plate and pivoted thereto at 17. Each lever 16 has a pivotal connection with one end of another lever 18 also pivoted to the bed plate at 19. The other end of the two levers 18 are pivotally connected to two slides 20, that operate in ways 21 formed on the underside of the bed plate and are attached to the clamp plates 3 and 4, by the two screws 22. These slides 20, are connected by spring 23, which tends to draw them together.

With this construction it will be seen that when the levers 16-18 of either pair are turned so as to swing them more nearly into line with each other, as illustrated in Fig. 2, the outer ends of the levers will be carried outwardly and as said outer ends are connected to one of the clamp plates, said clamp plate will be moved laterally away from the other clamp plate.

I have provided means accessible from the top of the bed plate 1, for controlling the relative position of the levers of each pair, thereby determining the initial position of the corresponding clamp plate.

For this purpose I have provided two rock shafts 25, which extend through the bed plate, each of which carries at its lower end a positioning arm 24, which is adapted to engage the levers of one pair at the point where they are pivotally connected. The upper end of each rock shaft 25, is provided with an arm 26 having the thumb piece 27. There is one such arm and its connections for each clamp plate.

The spring 23 tends at all times to draw the clamp plates toward each other, and the positioning element 24 constitutes means for limiting the inward movement of the clamp plates, and thus determining their initial position, before the spreading action occurs.

The construction above described provides a simple device by which the operator may quickly and easily adjust the clamp plates as to their initial position and thus determine the amount or degree to which the clamp plates will be spread during the relative movement of the parts from button-hole cutting to stitching position.

If the maximum spread is desired, then the arms 26 will be swung outwardly from the position shown in Fig. 1, this operation

turning the positioning members 24, so as to allow the connected ends of the levers 16-18 to swing outwardly, and the inner end to swing inwardly under the influence of the spring 23. This brings the clamp plates closer together, so that when the rolls 12 engage the cam surfaces 11, a greater spreading action will result. On the other hand if it is desired to have a small amount of spreading, the lever 26 will swing inwardly, which operation spreads the plates and gives them an initial position further apart, so that when the rolls 12 engage the surfaces 11, there will be less spreading movement.

By means of this construction the operator can adjust the clamp plates at any time by simply shifting the arms 26, and he is, therefore, able to instantly adjust his machine for different grades of goods.

I claim—

1. In a sewing machine having a bed plate, work-holding means carried thereby and comprising two clamp-plates capable of separating movement to spread the button-hole slit, a throat plate, said work-holding means and throat plate having a relative movement from button-hole cutting position to stitching position, and a spreader by which the clamp-plates are separated to a predetermined point during such relative movement, the combination with said clamp-plates and spreader, of a positioning device for determining the initial position of each clamp-plate and a swinging arm operating parallel to but above the bed plate and by which each positioning device is adjusted.

2. In a sewing machine having a bed plate, work-holding means carried thereby and comprising two clamp-plates capable of separating movement to spread the button-hole slit, a throat plate, said work-holding means and throat plate having a relative movement from button-hole cutting position to stitching position, and a spreader by which the clamp-plates are spread to a predetermined point during such relative movement, the combination with said spreader and clamp-plates, of two rock shafts extending through the bed plate, a positioning element on each rock shaft for determining the initial position of the corresponding clamp-plate, and an arm for operating each rock shaft located above the bed plate.

3. In a sewing machine having a bed plate, work-holding means carried thereby and comprising two clamp plates capable of separating movement to spread the button-hole slit, a throat plate, said work-holding means and throat plate having a relative movement from button-hole cutting position to stitching position and a spreader by which the clamp plates are separated to a predetermined point during such relative movement, the combination with said

- clamp plates and spreader, of two pairs of pivotally-connected levers, one for each clamp plate, each pair of levers being connected to the corresponding plate, a positioning device acting on each pair of levers thereby to determine the initial position of the corresponding plate, and means for adjusting the position of the positioning device.
4. In a sewing machine having a bed plate, work-holding means carried thereby and comprising two clamp plates capable of separating movement to spread the button-hole slit, a throat plate, said work-holding means and throat plate having a relative movement from button-hole cutting

position to stitching position and a spreader by which the clamp plates are separated to a predetermined point during such relative movement, the combination with said 20 clamp plates and spreader, of two pairs of pivotally-connected levers, one for each clamp plate, each pair of levers being connected to the corresponding plate, a positioning device acting on each pair of levers 25 thereby to determine the initial position of the corresponding plate, and a swinging arm above the bed plate for adjusting the position of each positioning device.

In testimony whereof, I have signed my 30 name to this specification.

JOHN KIEWICZ.
